(57) **CLAIM**

The ornamental design for a bumper for vehicle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a bumper for vehicle showing my new design;

FIG. 2 is a rear view thereof;

FIG. 3 is a front view thereof;

FIG. 4 is a top plan view thereof;

FIG. 5 is a left side view thereof, the right side being a mirror image thereof; and,

FIG. 6 is a bottom view thereof.
